Stanley A. Sherno, Grandview Road,
Ebensburg, Pa. 15931

Filed Feb. 24, 1967, Ser. No. 5,941

Term of patent 14 years

(Cl. D56—4)

FIG. 1.

FIG. 2.

FIG. 3.

FIG. 4.

FIG. 5.

FIG. 1 is a perspective view from above and the front of a stereophonic radio and phonograph cabinet, showing my new design;

FIG. 2 is a perspective view from above and the rear;

FIG. 3 is a front elevation;

FIG. 4 is an end elevation, both ends being similar in appearance; and

FIG. 5 is a perspective view similar to FIG. 1 but with the cabinet opened and the two end loudspeaker units pivoted from their forward direction toward one side.

The bottom surface is flat and rectangular supported on duplicate pairs of legs as shown in FIGS. 3 and 4.

The turntable and radio and phonograph control knobs shown in broken lines in FIG. 5 are for illustrative purposes only.

I claim:

The ornamental design for a stereophonic radio and phonograph cabinet, as shown and described.
